UNITED STATES PATENT OFFICE

BERNARD E. O'HAGAN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY TRAFFIC CONTROLLING APPARATUS

Application filed October 20, 1930. Serial No. 489,780.

My invention relates to railway traffic controlling apparatus, and particularly to apparatus of the type involving train carried governing mechanism controlled by energy received from the trackway. More particularly, my present invention relates to the trackway portion of such apparatus, and has for an object the provision of novel means for controlling the application of coded train controlling current to the track rails of a main section of railway track when one rail of such section has been divided to form an auxiliary section in which a car might stand without shunting the train controlling current away from the rails of the main section in rear of the auxiliary section.

I will describe two forms of apparatus embodying my invention, and will then point out the novel features thereof in claims.

In the accompanying drawings, Fig. 1 is a diagrammatic view illustrating one form of apparatus embodying my invention. Fig. 2 is a similar view showing a modified form of the apparatus illustrated in Fig. 1, and also embodying my invention.

Similar reference characters refer to similar parts in both views.

Referring first to Fig. 1, the reference characters 1 and 1^a designate the track rails of a stretch of railway track over which traffic normally moves in the direction indicated by the arrow. These track rails are divided by means of insulated joints 2, to form a plurality of main track sections, of which only two, A—B and B—C, are illustrated in the drawings. Each main track section is provided with a track circuit comprising a source of current, designated by the reference character T with a distinguishing exponent, and a main track relay, designated by the reference character R with a distinguishing exponent. As here shown, the source of current T for each main track section is a track transformer, the secondary 3 of which is connected across the rails of the section adjacent the exit end of the section in series with the usual current limiting impedance 4. The primary 6 of transformer T^c is constantly supplied with alternating current from the terminals X and Y of a suitable source of

current not shown in the drawings. The primary 6 of the transformer T^b is also supplied with alternating current from the terminals X and Y in a manner which will be described hereinafter. The track relay R for each section comprises two windings 7 and 8, the former of which, 7, is connected across the rails of the section adjacent the entrance end of the section, and the latter of which, 8, is constantly supplied with alternating current from the terminals X and Y.

The lower rail 1 of section A—B is divided, by means of insulated joints 2^a, to form an auxiliary track section 9, and the track circuit current for the main section A—B is carried around the auxiliary section 9 by a conductor 10. The auxiliary section 9 is provided with a track circuit comprising a transformer T^a and an auxiliary track relay R^a.

An auxiliary track section located within a main track section, and provided with a track circuit in the manner just described, is particularly suitable for, although in no way limited to, use in systems for controlling highway crossing signals, such for example, as the system disclosed and claimed in the pending application for Letters Patent of the United States Serial No. 468,538, filed by George W. Baughman, on July 17, 1930, for apparatus for the control of highway crossing signals. The means for controlling the highway crossing signals by the auxiliary track section forms no part of my present invention, and is therefore omitted from the drawings for the sake of simplicity. When an auxiliary track section of the type described is located within a main track section, however, and it is desired to supply the rails of the main track section with train controlling current which cooperates with train carried governing apparatus to control the movement of trains through the section, it is necessary to insure that no train controlling current will be supplied to the rails of the main section in the event that a single car is inadvertently left standing in the auxiliary section, because such a car would not shunt the train controlling current away from the rails of the main section in rear of the auxiliary section, and a dangerous condition might result. For this

100

purpose, I provide the apparatus which I will now proceed to describe.

This apparatus, as here shown, comprises a coding relay D, a checking relay F, a coder control relay E, and a slow releasing repeater relay G. The coding relay D, in the form here shown, comprises a winding 11, and two contacts 12 and 13 which are periodically operated at different frequencies when the relay is energized. For example, for purposes of illustration, I will assume that when coding relay D is energized, contact 12 is periodically operated at a frequency of 180 times per minute while contact 13 is periodically operated at a frequency of 80 times per minute.

Relay G is controlled by a front contact 23 of track relay R^B , and it will be apparent, therefore, that this relay is energized or de-energized according as track relay R^B is energized or deenergized.

Relay E is provided with a pick-up circuit which passes from terminal X through back contact 14 of track relay R^A , front contact 15 of track relay R^B , and the winding of relay E to terminal Y. Relay E is also provided with a stick circuit which passes from terminal X through back contact 14 of track relay R^A , front contact 16 of relay E, and the winding of relay E to terminal Y.

Relay F is provided with a pick-up circuit which passes from terminal X through front contact 17 of track relay R^A , front contact 18 of track relay R^B , back contact 19 of relay E, and the winding of relay F to terminal Y. Relay F is also provided with two stick circuits, one of which passes from terminal X through front contact 20 of track relay R^B , front contact 21 of relay F, and the winding of relay F to terminal Y, and the other of which passes from terminal X through back contact 22 of relay G, front contact 21 of relay F, and the winding of relay F to terminal Y.

Coding relay D is provided with a pick-up circuit which passes from terminal X through front point of contact 25 of relay F, front contact 24 of relay E, and winding 11 of relay D to terminal Y.

The primary 6 of transformer T^B is provided with one circuit which passes from terminal X through back contact 26 of relay E and primary 6 to terminal Y, and with another circuit which passes from terminal X through back point of contact 25 of relay F and primary 6 to terminal Y. When either of these circuits is closed, the rails of section A-B are supplied with uninterrupted track circuit current, and track relay R^A is energized. The primary 6 of transformer T^B is also provided with a circuit which passes from terminal X through front point of contact 25 of relay F, front contact 24 of relay E, contact 12 of relay D, front point of contact 27 of track relay R^B , and primary 6 to terminal Y.

When this circuit is closed, the rails of section A-B are supplied with alternating train controlling current which is periodically interrupted at a frequency of 180 times per minute, this current hereinafter being designated as high speed code. The primary 6 of transformer T^B is further provided with a circuit which passes from terminal X through front point of contact 25 of relay F, front contact 24 of relay E, contact 13 of relay D, back point of contact 27 of track relay R^B , and primary 6 to terminal Y. When this circuit is closed the rails of section A-B are supplied with alternating train controlling current which is periodically interrupted at 80 times per minute. This latter current I shall hereinafter designate as low speed code.

It should be pointed out that, while for purposes of illustrating my invention, I have shown means for periodically varying the train controlling current at only two rates, my invention is not limited to this number.

The train controlling current supplied to the rails of section A-B is intended for co-operation with train carried governing means forming no part of my invention, and is therefore not illustrated in the drawings. For purposes of the present disclosure, it is sufficient to say that, when high speed code is being supplied to the rails of section A-B, a train traversing the section will receive a proceed indication on board the train; when low speed code is being supplied to the rails of section A-B, a train traversing the section will receive a caution indication; and when no code is being supplied to the rails of the section, a train traversing the section will receive a slow indication.

As shown in the drawings, section A-B, the auxiliary section 9, and section B-C, are all unoccupied. The track relays R^A , R^B and R^B are therefore all energized. Both the pick-up and stick circuits for relay E are therefore open at back contact 14 of track relay R^A , and relay E is therefore deenergized. The pick-up circuit for relay F is closed so that this relay is energized, and relay G is also energized. Relay D, however, is deenergized, the circuit for this relay being open at front contact 24 of relay E.

In explaining the operation of the apparatus as a whole, I will first assume that with the parts in the conditions just described, a train enters section A-B. Track relay R^A will therefore become deenergized, and will open its front contact 17 and close its back contact 14. The opening of front contact 17 of track relay R^A will interrupt the pick-up circuit for relay F, but as long as track relay R^B is energized, the stick circuit for relay F including front contact 20 of track relay R^B will still be closed, and relay F will therefore remain energized. The closing of back contact 14 of track relay R^A will complete the pick-up circuit for relay E, and relay E

will therefore become energized, and will complete its stick circuit at its front contact 16. It will be apparent, therefore, that relay E will now remain energized over its 5 stick circuit, even though track relay R^9 becomes deenergized due to the train entering the auxiliary section 9. When relay E becomes energized, the supply of uninterrupted track circuit current to the rails of 10 section A—B will be cut off due to the opening of back contact 26 of relay E, and since relay F is still energized, coding relay D will become energized. High speed code will then be supplied to the rails of section A—B, 15 and as a result, the train will receive a proceed indication which permits it to proceed at full speed through the section. When the train enters section B—C, track relay R^B will become deenergized, and will 20 open its front contacts 20 and 23. The opening of front contact 20 of track relay R^B will interrupt the stick circuit which was previously closed for relay F at this contact, and the opening of front contact 23 of track 25 relay R^B will open the circuit for relay G. Due to the fact that relay G is slow releasing, a considerable interval of time will elapse after its circuit is opened, before it will close its back contact 22 and, since the stick circuit for relay F including contact 20 of track relay R^B is opened at the same time that the circuit for relay G is opened, by the time back contact 22 of relay G has become closed, 30 relay F will have become deenergized. It will be apparent, therefore, that under these conditions, the closing of back contact 22 of relay G will not complete the stick circuit for relay F including this contact. The deenergization of relay F will deenergize coding relay D, and will also interrupt the supply of train controlling current to the rails of section A—B. Furthermore, the deenergization of relay F will complete the circuit for primary 6 of transformer T^B including 35 the back point of contact 25, so that after the train has passed completely out of section A—B, the rails of this section will be supplied with track circuit current which will pick up track relay R^A . This, in turn, will deenergize relay E, thereby completing the 40 circuit for primary 6 of transformer T^B including back contact 26 of relay E. If track relay R^9 is then energized, as will be the case if no car has been left standing in auxiliary section 9, the deenergization of relay E will also complete the pick-up circuit for relay F, and relay F will pick up. When 45 relay F picks up, it will interrupt the circuit for the primary 6 of transformer T^B which was previously closed at back point of contact 25 of this relay, and it will also complete its stick circuit including back contact 22 of relay G. It follows that if a following train 50 now enters section A—B, relay F will remain energized. When the train has passed

completely out of section B—C, track relay R^B will pick up and will complete the stick circuit for relay F including contact 20, as well as the circuit for relay G. Relay G will therefore pick up, and the apparatus will 70 then be restored to the condition in which it is illustrated in the drawings. It will be noted that during the picking up of track relay R^B , there is no interruption in the supply of current to relay F because the stick circuit for relay F including contact 20 of track relay R^B becomes closed before the stick circuit for relay F including back contact 22 of relay G becomes opened. 75

If a second train enters section A—B before the preceding train has left the section, the second train will not receive train controlling current even after the first train has passed completely out of this section. For, as soon as the first train enters section B—C 80 and deenergizes track relay R^B , relay F will become deenergized in the manner previously described and when this first train passes completely out of section A—B, relay R^A will remain deenergized due to the second 85 train. As long as relay R^A is deenergized, the pick-up circuit for relay F will be open at front contact 17 of track relay R^A , and relay F cannot, therefore, be again energized to complete the circuit for coding relay D. The following train will therefore receive a 90 slow indication throughout section A—B under these conditions. 95

I will now assume that a following train enters section A—B after a preceding train has passed completely out of this section but is still in section B—C. Under these conditions, at the instant the following train enters the section A—B, track relays R^A and R^9 and relay F will all be energized, but relays E, G and D, and track relay R^B will all be deenergized. As a result, when relay R^A becomes shunted by the train, it will complete the pick-up circuit for relay E in the manner previously described, and will interrupt the pick-up circuit for relay F. Relay F will not become deenergized under these conditions, however, because, since relay G is now deenergized, the stick circuit for relay F including contact 22 of relay G 100 will be closed. When relays E and F are both energized, the circuit for coding relay D is completed, and relay D will become energized. Low speed code will then be supplied to the rails of section A—B over back point of contact 27 of track relay R^B , and the train will therefore receive a caution indication as it proceeds through the section. When the following train has passed out of section A—B, track relays R^A and R^9 will 105 both become energized. Relay E will therefore become deenergized, and will deenergize coding relay D. When the following train has passed out of section B—C, (it being understood that the preceding train 110

114

120

125

130

passed out of this section before or shortly after the following train entered the section) track relay R^B will pick up and will complete the circuit for relay G , so that 5 this relay will also pick up. The apparatus will then be restored to the conditions in which it is illustrated in the drawings.

I will next assume that a first train leaves a car standing within the auxiliary section 10 which would not shunt current away from the rails of the main section A—B in rear of the auxiliary section, and that after the first train has passed completely out of section A—B, a second train enters the section. 15 As long as auxiliary section 9 is occupied by the car, track relay R^a will be deenergized, and since the pick-up circuit for relay F includes a front contact 18 of track relay R^a , it follows that relay F , which became 20 deenergized when the first train entered section B—C, is prevented from again becoming energized as long as the car occupies the auxiliary section. When relay F is deenergized, the circuit for coding relay D is open 25 at front point of contact 25 of relay F , and no train controlling current can be supplied to the rails of section A—B. As a result, when the following train enters section A—B, under these conditions, a slow indication will 30 be received on the train, and it will be apparent, therefore, that a dangerous condition would not exist.

In the modification shown in Fig. 2, the use of relay F has been rendered unnecessary by providing relay E with two stick circuits which are controlled by relays R^B and G , respectively. The stick circuit for relay E which is controlled by relay R^B passes from terminal X through back contact 14 35 of track relay R^A , front contact 20 of track relay R^B , front contact 16 of relay E , and the winding of relay E to terminal Y . The stick circuit for relay E which is controlled by relay G passes from terminal X through 40 back contact 14 of track relay R^A , back contact 22 of relay G , front contact 16 of relay E , and the winding of relay E to terminal Y . Relay D , as here shown, is controlled 45 solely by a front contact 24 of relay E . The remainder of the apparatus is substantially 50 the same as that shown in Fig. 1.

In explaining the operation of the apparatus shown in Fig. 2, I will first assume that with the parts in the conditions in which they 55 are illustrated in the drawings, a train enters section A—B. This deenergizes track relay R^A , and since relay R^a is energized, the pick-up circuit for relay E then becomes closed. Relay E therefore becomes energized, and 60 completes its stick circuit including front contact 20 of track relay R^B , so that relay E will now remain energized as long as front contact 20 of track relay R^B remains closed. When relay E is energized, the supply of 65 track circuit current to the primary 6 of

transformer T^B is interrupted at back contact 26 of relay E , and the circuit for relay D is completed at front contact 24 of relay E . Relay D therefore becomes energized, and since relay R^B is now energized, high speed code is supplied to section A—B. The 70 train may therefore proceed at full speed through the section. When the train enters section B—C, the shunting of track relay R^B deenergizes relay G and also interrupts the 75 stick circuit which was previously closed for relay E at front contact 20 of track relay R^B . When the stick circuit for relay E is interrupted, relay E becomes deenergized, with the result that relay E cannot again become 80 energized unless track relay R^a is picked up, thereby insuring that train controlling current will not be supplied to section A—B and a following train, if a car should be left standing in section 9 by the first train. Furthermore, when relay E becomes deenergized, the circuit for primary 6 of transformer T^B including back contact 26 of relay E is completed, so that when the train has passed 85 completely out of section A—B, track circuit current is supplied to track relay R^A and this relay picks up. When the train passes out of section B—C, track relay R^B again becomes energized and energizes relay G . The parts are then restored to the positions in 90 which they are illustrated in the drawings.

I will now assume that after a first train has passed completely out of section A—B, but is still in section B—C, a following train enters section A—B. When track relay R^A becomes shunted by the following train, relay E will become energized as previously described, and will complete the circuit for coding relay D . Coding relay D will therefore become energized, and since track relay R^B is now deenergized, low speed code will 100 be supplied to the rails of section A—B. The energization of relay E , under these conditions, will also complete its stick circuit including back contact 22 of relay G . As a result, if the preceding train now leaves section B—C, relay E will remain energized because when track relay R^B picks up, its front contact 20 will become closed and will complete the other stick circuit for relay E before 105 relay G becomes energized and interrupts the stick circuit for relay E including back contact 22 of relay G . With relay E energized and track relay R^B picked up, the rails of section A—B in advance of the following train will be supplied with high speed code, and the following train may proceed through the remainder of section A—B at full speed. When the following train passes out of section 110 A—B, the coded current supplied to the rails will pick up track relay R^A , which will interrupt the stick circuit for relay E and hence deenergize relay E . When the following train has passed completely out of section B—C, track relay R^B and, hence, re-

lay G, will again become energized. The parts will then be restored to the condition in which they are illustrated in the drawings.

- 5 It should be pointed out that the supply of current to the primary 6 of transformer T^c may be periodically varied in well known manner to produce coded train controlling current for influencing the train carried apparatus of a train occupying section B—C. Means for producing this result have no bearing upon the present disclosure and are not shown in the drawings.

Although I have herein shown and described only two forms of railway traffic controlling apparatus embodying my invention, it is understood that various changes and modifications may be made therein within the scope of the appended claims without departing from the spirit and scope of my invention.

Having thus described my invention, what I claim is:

1. In combination, a first main section of railway track, one of the rails of which is divided to form an auxiliary section, a track circuit for said main section including a main track relay, a track circuit for said auxiliary section including an auxiliary track relay, a third relay controlled by said two track relays, and means controlled by said third relay for supplying train controlling current to the rails of said main section.
2. In combination, a first main section of railway track, one of the rails of which is divided to form an auxiliary section, a track circuit for said main section including a main track relay, a track circuit for said auxiliary section including an auxiliary track relay, a third relay controlled by a back contact of said main track relay and a front contact of said auxiliary track relay, and means controlled by said third relay for supplying train controlling current to the rails of said main section.
3. In combination, a first main section of railway track, one of the rails of which is divided to form an auxiliary section, a track circuit for said main section including a main track relay, a track circuit for said auxiliary section including an auxiliary track relay, a third relay, a pick-up circuit for said third relay including a back contact of said main track relay and a front contact of said auxiliary track relay, a stick circuit for said third relay including said back contact of said main track relay and a front contact of said third relay, and means controlled by said third relay for supplying train controlling current to the rails of said main section.

4. In combination, a first main section of railway track, one of the rails of which is divided to form an auxiliary section, a second main section of railway track adjacent the exit end of said first main section, a track circuit for said first main section including a first main track relay, a track circuit for said second main section including a second main track relay, a track circuit for said auxiliary including an auxiliary track relay, a slow releasing relay controlled by said second main track relay, and means controlled by all of said relays for supplying train controlling current to the rails of said first main section.
5. It should be pointed out that the supply of current to the primary 6 of transformer T^c may be periodically varied in well known manner to produce coded train controlling current for influencing the train carried apparatus of a train occupying section B—C. Means for producing this result have no bearing upon the present disclosure and are not shown in the drawings.

circuit for said first main section including a first main track relay, a track circuit for said auxiliary section including an auxiliary track relay, a track circuit for said second main section including a second main track relay, a fourth relay controlled by said first main track relay and by said auxiliary track relay, and means for supplying train controlling current to the rails of said first main section controlled by said fourth relay and by said second main track relay.

5. In combination, a first main section of railway track, one of the rails of which is divided to form an auxiliary section, a second main section of railway track adjacent said first main section, a track circuit for said first main section including a first main track relay, a track circuit for said auxiliary section including an auxiliary track relay, a track circuit for said second main section including a second main track relay, and means controlled by said three track relays for supplying train controlling current to the rails of said first main section.

6. In combination, a first main section of railway track, one of the rails of which is divided to form an auxiliary section, a second main section of railway track adjacent said first main section, a track circuit for said first main section including a first main track relay, a track circuit for said auxiliary section including an auxiliary track relay, a track circuit for said second main section including a second main track relay, a fourth relay controlled by said three track relays, and means controlled by said fourth relay and by said second main track relay for supplying train controlling current to the rails of said first main section.

7. In combination, a first main section of railway track one of the rails of which is divided to form an auxiliary section, a second main section of railway track adjacent the exit end of said first main section, a track circuit for said first main section including a first main track relay, a track circuit for said second main section including a second main track relay, a track circuit for said auxiliary section including an auxiliary track relay, a slow-releasing relay controlled by said second main track relay, and means controlled by all of said relays for supplying train controlling current to the rails of said first main section.

8. In combination, a first main section of railway track, one of the rails of which is divided to form an auxiliary section, a second main section of railway track adjacent the exit end of said first main section, a track circuit for said first main section including a first main track relay, a track circuit for said second main section including a second main track relay, a track circuit for said auxiliary including an auxiliary track relay, a slow releasing relay controlled by said

second main track relay; a fifth relay controlled by said slow releasing relay, said first main track relay and said auxiliary track relay; and means controlled by said fifth relay for supplying train controlling current to the rails of said first main section.

9. In combination, a first main section of railway track, one of the rails of which is divided to form an auxiliary section, a second main section of railway track adjacent the exit end of said first main section, a track circuit for said first main section including a first main track relay, a track circuit for said second main section including a second main track relay, a track circuit for said auxiliary section including an auxiliary track relay, a slow releasing relay controlled by said second main track relay; a fifth relay controlled by said slow releasing relay, said first main track relay and said auxiliary track relay; and means controlled by said fifth relay, and by said second main track relay for supplying train controlling current to the rails of said first main section.

25 10. In combination, a first main section of railway track, one of the rails of which is divided to form an auxiliary section, a second main section of railway track adjacent the exit end of said first main section, a track circuit for said first main section including a first main track relay, a track circuit for said auxiliary section including an auxiliary track relay, a track circuit for said second main section including a second main track relay, a fourth relay controlled by said three track relays, a coding relay controlled by said fourth relay, and means controlled by said coding relay and by said fourth relay for supplying train controlling current to the rails of said first main section.

30 35 40

11. In combination, a first main section of railway track, one of the rails of which is divided to form an auxiliary section, a second main section of railway track adjacent to the exit end of said first main section, a track circuit for said first main section including a first main track relay, a track circuit for said auxiliary section including an auxiliary track relay, a track circuit for said second main section including a second main track relay, a fourth relay controlled by said three track relays, a coding relay controlled by said fourth relay, and means controlled by said coding relay, said fourth relay and said second main track relay for supplying train controlling current to the rails of said first main section.

12. In combination, a first main section of railway track, one of the rails of which is divided to form an auxiliary section, a second main section of railway track adjacent to the exit end of said first main section, a track circuit for said first main section including a first main track relay, a track circuit for said auxiliary track section including an

auxiliary track relay, a track circuit for said second main section including a second main track relay, a fourth relay, a pick-up circuit for said fourth relay including a back contact of said first main track relay and a front contact of said auxiliary track relay, a stick circuit for said fourth relay including said back contact of said first main track relay and a front contact of said fourth relay, a slow releasing relay controlled by a front contact of said second main track relay, a sixth relay; a pick-up circuit for said sixth relay including a front contact of said first main track relay, a front contact of said auxiliary track relay, and a back contact of said fourth relay; a first stick circuit for said sixth relay including a front contact of said second main track relay and a front contact of said sixth relay, a second stick circuit for said sixth relay including a back contact of said slow releasing relay and a front contact of said sixth relay, and means controlled by said fourth and sixth relays for supplying train controlling current to the rails of said first main section.

13. In combination, a first main section 90 of railway track, one of the rails of which is divided to form an auxiliary section, a second main section of railway track adjacent the exit end of said first main section, a track circuit for said first main section 95 including a first main track relay, a track circuit for said auxiliary track section including an auxiliary track relay, a track circuit for said second main section including a second main track relay, a fourth relay, a pick-up circuit for said fourth relay including a back contact of said first main track relay and a front contact of said auxiliary track relay, a stick circuit for said 100 fourth relay including said back contact of said first main track relay and a front contact of 105 said fourth relay, a slow releasing relay controlled by a front contact of said second main track relay, a sixth relay; a pick-up circuit for said sixth relay including a front contact of said first main track relay, a front contact of said auxiliary track relay, and a back contact of said fourth relay; a first stick circuit for said sixth relay including a front contact of said second 110 main track relay and a front contact of said sixth relay, a second stick circuit for said sixth relay including a back contact of said slow releasing relay and a front contact of 115 said sixth relay, and means controlled by a front contact of said fourth relay and a front contact of said sixth relay for supplying train controlling current to 120 the rails of said first main section.

14. In combination, a first main section 125 of railway track, one of the rails of which is divided to form an auxiliary section, a second main section of railway track adjacent the exit end of said first main section, a track circuit for said first main section in- 130

cluding a first main track relay, a track circuit for said auxiliary track section including an auxiliary track, relay, a track circuit for said second main section including a second main track relay, a fourth relay, a pick-up circuit for said fourth relay including a back contact of said first main track relay and a front contact of said auxiliary track relay, a stick circuit for said fourth relay including said back contact of said first main track relay and a front contact of said fourth relay, a slow releasing relay controlled by a front contact of said second main track relay, a sixth relay; a pick-up circuit for said sixth relay including a front contact of said first main track relay, a front contact of said auxiliary track relay, and a back contact of said fourth relay; a first stick circuit for said sixth relay including a front contact of said second main track relay and a front contact of said sixth relay, a second stick circuit for said sixth relay including a back contact of said slow releasing relay and a front contact of said sixth relay, and means controlled by said fourth, said sixth and said second main track relays for supplying train controlling current to the rails of said first main section.

15. In combination, a first main section of railway track, one of the rails of which is divided to form an auxiliary section, a second main section of railway track adjacent the exit end of said first main section, a track circuit for said first main section including a transformer having its secondary connected across the rails at one end of the section and a first main track relay connected with the rails at the other end of the section, a track circuit for said auxiliary track section including an auxiliary track relay, a track circuit for said second main section including a second main track relay, a fourth relay, a pick-up circuit for said fourth relay including a back contact of said first main track relay and a front contact of said auxiliary track relay, a stick circuit for said fourth relay including said back contact of said first main track relay and a front contact of said fourth relay, a slow releasing relay controlled by a front contact of said second main track relay, a pick-up circuit for said sixth relay including a front contact of said first main track relay, a front contact of said auxiliary track relay, and a back contact of said fourth relay; a first stick circuit for said sixth relay including a front contact of said second main track relay and a front contact of said sixth relay, a second stick circuit for said sixth relay including a back contact of said sixth relay and a front contact of said slow releasing relay and a front contact of said sixth relay, a coding relay controlled by a front contact of said fourth relay and provided with a first contact which is periodically operated at one frequency when said coding relay is energized and a second contact

which is periodically operated at a different frequency when the relay is energized, a first circuit for the primary of said transformer including a source of current and a back contact of said fourth relay; a second circuit for the primary of said transformer including a source of current, a front contact of said fourth relay, said first contact of said coding relay, a front contact of said second main track relay, and a front contact of said sixth relay; and a third circuit for the primary of said transformer including a front contact of said fourth relay, said second contact of said coding relay, a back contact of said second main track relay, and a front contact of said sixth relay.

16. In combination, a first main section of railway track, one of the rails of which is divided to form an auxiliary section, a second main section of railway track adjacent the exit end of said first main section, a track circuit for said first main section including a first main track relay, a track circuit for said auxiliary track section including an auxiliary track relay, a track circuit for said second main section including a second main track relay, a fourth relay, a slow releasing relay controlled by a front contact of said second main track relay, a pick-up circuit for said fourth relay including a back contact of said first main track relay and a front contact of said auxiliary track relay, a first stick circuit for said fourth relay including a back contact of said first main track relay, a front contact of said second main track relay, and a front contact of said fourth relay; a second stick circuit for said fourth relay including a back contact of said first main track relay, a back contact of said slow releasing relay, and a front contact of said fourth relay, and means controlled by said fourth relay for supplying train controlling current to the rails of said first main section.

17. In combination, a first main section of railway track, one of the rails of which is divided to form an auxiliary section, a second main section of railway track adjacent to the exit end of said first main section, a track circuit for said first main section including a transformer having its secondary connected across the rails at one end of the section and a first main track relay connected with the rails at the other end of the section, a track circuit for said auxiliary track section including an auxiliary track relay, a track circuit for said second main section including a second main track relay, a fourth relay, a slow releasing relay controlled by a front contact of said second main track relay, a pick-up circuit for said fourth relay including a back contact of said first main track relay and a front contact of said auxiliary track relay, a first stick circuit for said fourth relay including a back contact of said first main track relay, a front contact of said sec- 110 115 120 125 130

ond main track relay, and a front contact of said fourth relay; a second stick circuit for said fourth relay including a back contact of said first main track relay, a back contact of said slow releasing relay, and a front contact of said fourth relay, a coding relay controlled by a front contact of said fourth relay and provided with a first contact which is periodically operated at one frequency when said coding relay is energized and with a second contact which is periodically operated at a different frequency when the relay is energized, a first circuit for the primary of said transformer including a source of current and a back contact of said fourth relay; a second circuit for the primary of said transformer including a source of current, a front contact of said fourth relay, said first contact of said coding relay, and a front contact of said second main track relay; and a third circuit for the primary of said transformer including a front contact of said fourth relay, said second contact of said coding relay, and a back contact of said second main track relay.

18. In combination, a first main section of railway track, one of the rails of which is divided to form an auxiliary section, a track circuit for said main section including a main track relay, a track circuit for said auxiliary section including an auxiliary track relay, and means controlled by said two track relays for supplying train controlling current to the rails of said main section.

19. In combination, a first main section of railway track, one of the rails of which is divided to form an auxiliary section, and means effective upon the entrance of a train into said main section for at times supplying the rails of said main section with train controlling current provided said auxiliary section is unoccupied.

In testimony whereof I affix my signature.

BERNARD E. O'HAGAN.
